REFRIGERATION

Application filed December 20, 1930. Serial No. 503,847.

This invention relates to refrigeration, and particularly to means for controlling the feed of liquid refrigerant to flooded evaporators.

In my allowed application Serial No. 408, 5363, filed November 19, 1929, I describe and claim an arrangement of float control valve for feeding liquid refrigerant to a flooded evaporator in which the float valve is located at a level above the liquid level in the evapo- 10 rator.

Generally stated, the float responds to the rise and fall of a column of liquid, preferably refrigerant, which balances a liquid column in the evaporator, the two columns reacting against each other through a pressure transmitting link of refrigerant vapor.

In the structure of the prior application, no means was provided for varying the liquid level maintained in the evaporator, and the 20 object of the present invention is to provide such means.

The present invention contemplates the adjustment of the vertical height of the pressure transmitting link of refrigerant vapor. 25 This may be done in various ways, for example, the vertical height of the upper end of the link may be varied, in which case the height of both liquid columns will vary to correspond.

According to another embodiment of the invention the vertical height of the lower end of the vapor column is varied, in which case the height of both liquid columns remains the same, but the datum plane for the 35 liquid column in the evaporator varies as the lower end of the vapor column varies in height.

Two embodiments of the invention, one embodying each of the general operative 40 principles above outlined, are illustrated in the accompanying drawings, in which,

Fig. 1 is a vertical elevation of a portion of an evaporator including a suction trap with the invention applied in that form in 45 which the vertical height of the upper end of the vapor column is adjustable. In this view, portions are sectioned to show the internal construction, and the parts are shown in the position for maintaining the lowest 50 available liquid level in the trap.

Fig. 2 is a section on line 2—2 of Fig. 1. In this view there is shown in full lines the adjustment for the lowest available liquid level, and in dotted lines an adjustment for a higher level.

Fig. 3 is a view similar to Fig. 1, showing a modified form in which the level of the lower end of the vapor column is adjustable.

Referring first to Figs. 1 and 2, an evaporator of the type described and claimed in the patent to Shipley No. 1,718,313, is indicated, but any flooded evaporator or similar closed volume, in which a definite level of liquid refrigerant is to be maintained, might be substituted.

The vertical drum 6 serves as a receiver suction trap. The lower or liquid headers of the evaporator are indicated at 7 and the upper or gas headers at 8. These are horizontal and are connected by riser tubes 9, of any suitable form, for example, the V-shaped riser tubes characteristic of the patent above identified. The form, or even the presence of the riser tubes, is not, however, material to the invention.

The minimum liquid operating level in the evaporator is indicated by the line A—A and another higher liquid level which may be maintained is indicated by the line B—B.

Connected to the upper end of the drum 6 is a suction line 11 which leads to the suction of the compressor, not shown. The liquid supply line 12 is connected to deliver liquid refrigerant to the drum 6 either 85 through a float control valve (normal operation) or through an expansion valve, but before describing the connections, the construction and arrangement of the float control valve will be explained.

The float valve mechanism includes a float chamber housing 13. From the top of this there leads a pressure equalizing connection 14 to the interior of the drum 6 above the highest liquid level to be maintained therein. 95 This connection is controlled by a normally open stop valve 15. From the bottom of the float chamber housing 13 a pipe 16 leads to the interior of the drum 6, at a point below the lowest liquid level to be maintained in 100

the drum. A liquid sealed trap is interposed between the pipe 16 and the drum 6, and, in the embodiment of the invention here illustrated, this takes the form of an inverted U, 5 17, having at its ends alined nipples 18 and 19, one of which swivels in the gland 21 at the lower end of the pipe 16, and the other of which swivels in a similar gland 22 connected directly to the interior of the drum 6 below 10 the lowest liquid level to be maintained therein. A brace is shown at 20.

The right hand leg of the inverted U-trap 17 is liquid filled, and the left hand leg is 15 filled with refrigerant gas or vapor, as is clearly indicated in Fig. 1. The vertical height defined by this trap is indicated by the line C—C and may be adjusted to vary the vertical height of the vapor column by tilting the member 17 from the vertical position indicated in full lines in Fig. 2 to an inclined position, one of which is indicated in 20 dotted lines in that figure.

The presence of vapor in the left hand leg 25 of the trap 17 is assured by the fact that the vapor evolved from any liquid in this leg is trapped against escape, and, consequently, displaces the liquid downward and into the drum 6, until the left hand leg of the trap 17 30 is free of liquid.

The liquid level maintained in the trap 35 chamber 13 is indicated by the line D—D. When the liquid rises in the chamber 13 to the level D—D, the float valve stops the feed and prevents the level from rising higher. A normally open stop valve 23 controls flow 35 through the pipe 16.

In the position illustrated in Fig. 1, and in the full line position of Fig. 2, the liquid 40 column H' balances the liquid column H², the pressure between the columns being transmitted through the vapor. The vapor column serves as a substantially weightless pressure-transmitting medium interposed between the two columns H', H².

If it is desired to raise the liquid level in 45 the drum 6, the trap 17 is swung to an inclined position (one of which is indicated in dotted lines in Fig. 2). In the position shown in dotted lines, the liquid column H³, 50 which is higher than the liquid column H', balances an equal liquid column H⁴, which, consequently, is higher than the liquid column H². Thus the angular adjustment of the trap member 17 permits adjustment of 55 the liquid level in the drum 6.

While the float valve mechanism might assume various forms and be variously connected, the following construction and arrangement is preferred:

Within the float chamber 13 is a float 24 carried by a rod 25 which is pivoted at 26. The rod 25 has an offset arm 27 which is connected to reciprocate a balanced piston slide 60 valve 28. This valve is conventionally illustrated as provided with a port groove 29,

which, in the lower position of the float, connects an inlet port 31 with an outlet port 32. Leading from the outlet port 32 is a bleed port 33, which, when the valve 29 is in its open position, delivers a small flow of liquid 70 refrigerant to the interior of the chamber 13. When the liquid in the chamber 13 falls below the level D—D, descent of the float 24 shifts the valve 28 to the left so that the port 29 connects the ports 31 and 32. At the level 75 D—D the valve 28 laps the port 32 and stops the flow.

Liquid refrigerant arriving by the high pressure liquid line 12 passes through a normally open stop valve 34 to a strainer 35 and thence by pipe 36 to the port 31. When the valve 28 is open, all the liquid except the small part which passes through the port 33 to the chamber 13, flows through the pipe 37 and normally open stop valve 38 to the pipe 39, and thence to the interior of the drum 6. A normally closed by-pass valve 41 which may be used as an expansion valve is provided, so that if it is desired to suspend the flow, the controlling valves 34 and 38 may be closed and the valve 41 may be opened, in which case liquid refrigerant will be fed to the drum directly.

The port 33 has an important function. Since the space within the chamber 13 is connected with the vapor space in the drum 6 by the equalizing connection 14, some refrigerant will evaporate in the chamber 13. The port 33 is designed to feed refrigerant to the chamber 13 at a rate slightly in excess of the maximum loss of refrigerant from the chamber by evaporation. The excess, which is slight, flows down the pipe 16, up the right hand leg of the trap 17, and then passes through the gas filled leg of the trap 17 to the lower end of the drum 6.

The supply of liquid to the chamber 13 is very limited, so limited that most of the refrigerant so fed passes off as vapor through the connection 14. The slight excess which is provided is not sufficient to flood the gas filled leg of the member 17, and thus exerts no disturbing effect.

The construction of the float valve has been illustrated in a simple and somewhat diagrammatic form, and may be departed from in practice. For example, I contemplate the use of the float valve illustrated in detail in my allowed application, above referred to, but as the function of that valve is in no way different from the function of the valve just described, it is unnecessary to illustrate it in detail.

It will be observed that the effect of inclining the member 17 is to vary the height of the upper end of the gas filled leg and simultaneously to vary the height of the two liquid columns which balance each other.

Other arrangements are possible. For example, it is possible to vary the position of

the lower end of the gas filled pipe. One such structure is illustrated in Fig. 3, and in this particular embodiment, the effective length of the gas filled pipe, only, is varied, 5 the height of the two balanced liquid columns remaining constant. However, this varies the datum plane, from which the column in the evaporator is measured, with the result that the actual level in the evaporator 10 drum is changed.

In Fig. 3 the construction and arrangement of many parts are unchanged, and accordingly they bear the same reference numerals as identical parts in Figs. 1 and 2. 15 Such identical parts are those numbered 6 to 16 inclusive, 23, and 34 to 41 inclusive. In Fig. 3 the internal construction of the float valve mechanism, indicated generally by the numeral 13, is not shown, but it is to 20 be understood that it conforms to the showing in Fig. 1 and contains the parts 24 to 33 inclusive.

The pipe 16 instead of leading to a swinging inverted trap 17, is formed with a trap 25 loop 42, which leads by an offset 43 into the relatively large vertical pipe 44 which communicates at its lower end with the drum 6, at a level lower than the lowest level to be maintained in the drum. The upper end of 30 the pipe 44, above the offset 43, is provided with a packing gland 45, through which is slidably adjustable in a vertical direction, a dip pipe 46. The upper end of the dip pipe 46 is connected by a flexible tube 47 with the 35 interior of the drum 6 above the highest liquid level to be maintained therein. A convenient way of making the connection is to connect the flexible pipe 47 directly with the pressure equalizing pipe 14, as shown in 40 Fig. 3.

An annular space is afforded between the outside of the dip pipe 46 and the inner side of the vertical pipe 44. Consequently, refrigerant vapor evolved in the pipe 44 is 45 trapped and displaces liquid refrigerant in the pipe 44 down to the level of the lower end of the dip pipe 46. It follows, therefore, that the effective liquid column in the trap 13, which is represented at H_5 , is balanced by 50 the effective liquid column H^6 in the drum 6.

The datum line E—E is determined by the lower end of the dip pipe 46, for as soon as the gas displaces the liquid downward in the pipe 44 to this datum line, the displacement 55 will be arrested by the escape of the gas upwardly through the dip pipe 46. In this arrangement the column H^6 is constant, and being equal to the column H^6 the latter must 60 also be a constant, but since the column H^6 is measured from the datum plane E—E and since the datum plane E—E may be adjusted vertically by adjusting the dip pipe 46 vertically, it is possible to establish different levels in the drum 6 by moving the dip pipe 46 up and down.

Both these arrangements have in common the feature that the vertical height of the gas or vapor leg which serves as a pressure transmitting link between the two liquid columns, is adjustable. 70

Various other arrangements within the scope of the invention are possible, and are contemplated. The gist of the invention is the use of a float control valve located at a fixed level, and preferably at a level above 75 the liquid level to be maintained in the evaporator, to maintain various desired levels in the evaporator, the result being secured by control of the gas filled link which serves as a pressure transmitting medium between the 80 two liquid columns, i. e., that controlled by the float, and that existing in the evaporator.

In certain of the claims the portion of pipe 16 above the seal afforded by the inverted U-trap 17 (Figs. 1 and 2), or above the seal 85 afforded by the loop 42 (Fig. 3), together with the liquid-filled portion of chamber 13, are referred to as a "liquid-containing manometer" for in effect such liquid column functions as a manometer. 90

What is claimed is,—

1. The combination with an evaporator, of means for maintaining a desired liquid level therein, comprising a liquid containing manometer; a valve controlling the supply of 95 liquid refrigerant to the evaporator; operating means for said valve responsive to the height of the liquid in said manometer; a pressure transmitting connection between said manometer and a point within the evaporator below the liquid level therein; means for developing in said connection a vapor pressure at least equal to the head of the liquid refrigerant at said point; and means for varying the vertical height of the vapor 100 filled portion of said pressure transmitting connection.

2. The combination with an evaporator, of means for maintaining a desired liquid level therein, comprising a liquid containing manometer; a valve controlling the supply of 110 liquid refrigerant to the evaporator; operating means for said valve responsive to the height of the liquid in said manometer; a pressure equalizing connection between the 115 upper end of the manometer and the vapor space above the liquid in the evaporator; a pressure transmitting connection between said manometer and a point within the evaporator below the liquid level therein; means for developing in said connection a vapor pressure at least equal to the head of the liquid refrigerant at said point; and means for varying the vertical height of the vapor 120 filled portion of said pressure transmitting connection.

3. The combination with an evaporator, of means for maintaining a desired liquid level therein, comprising a manometer containing a column of liquid refrigerant; a 130

- valve controlling the supply of liquid refrigerant to the evaporator; operating means for said valve responsive to the height of the liquid column in said manometer; a pressure transmitting connection between said manometer and a point within the evaporator below the liquid level therein; means for developing in said connection a refrigerant vapor pressure at least equal to the head of the liquid refrigerant at said point; and means for varying the vertical height of the vapor filled portion of said pressure transmitting connection.
4. The combination with an evaporator, of means for maintaining a desired liquid level therein, comprising a manometer containing a column of liquid refrigerant, a valve controlling the supply of liquid refrigerant to the evaporator; operating means for said valve responsive to the height of the liquid column in said manometer; a pressure equalizing connection between the upper end of the manometer and the vapor space above the liquid in the evaporator; a pressure transmitting connection between said manometer and a point within the evaporator below the liquid level therein; means for developing in said connection a refrigerant vapor pressure at least equal to the head of the liquid refrigerant at said point; and means for varying the vertical height of the vapor filled portion of said pressure transmitting connection.
5. The combination with an evaporator, of means for maintaining a desired constant liquid level therein, comprising a manometer containing a column of liquid refrigerant; a valve controlling the supply of liquid refrigerant to the evaporator; operating means for said valve responsive to the height of the liquid column in said manometer; a pressure equalizing connection between the upper end of the manometer and the vapor space above the liquid in the evaporator; a pressure transmitting connection between said manometer and a point within the evaporator below the liquid level therein; means for developing in said connection a refrigerant vapor pressure at least equal to the head of the liquid refrigerant at said point; means for varying the vertical height of the vapor filled portion of said pressure transmitting connection; and means for supplying liquid refrigerant to said manometer column at a restricted rate.
6. The combination with an evaporator, of means for maintaining a desired constant liquid level therein, comprising a valve controlling the supply of liquid refrigerant to the evaporator; a float chamber and a liquid sealed trap arranged to define a manometer column; a pressure equalizing connection from the float chamber to the vapor space of the evaporator; a pressure transmitting vapor filled connection between the trap and a point within the evaporator below the liquid level therein; a float in said float chamber connected to close said valve upon a rise of liquid level in said chamber; and means for feeding liquid refrigerant at a restricted rate to said chamber.
7. The combination with an evaporator, of means for maintaining a desired constant liquid level therein comprising a valve controlling the supply of liquid refrigerant to the evaporator; a float chamber and a liquid sealed trap arranged to define a manometer column; means for adjusting the vertical height of said trap, whereby the height of the manometer column is varied; a pressure equalizing connection from the float chamber to the vapor space of the evaporator; a pressure transmitting connection between the trap and a point within the evaporator below the liquid level therein; and a float in said float chamber connected to close said valve upon a rise of liquid level in said chamber.
8. The combination with an evaporator, of means for maintaining a substantially constant liquid level therein comprising a valve controlling the supply of liquid refrigerant to the evaporator; a float chamber and a liquid sealed trap arranged to define a manometer column; a pressure equalizing connection from the float chamber to the vapor space of the evaporator; a pressure transmitting vapor filled connection between the trap and a point within the evaporator below the liquid level therein; means for variably defining the lower end of said vapor filled connection; and a float in said float chamber connected to close said valve upon a rise of liquid level in said chamber.
9. The combination with an evaporator, of means for maintaining a desired liquid level therein comprising a valve controlling the supply of liquid refrigerant to the evaporator; a float chamber and a liquid sealed trap arranged to define a manometer column; means for adjusting the vertical height of said trap; a pressure equalizing connection from the float chamber to the vapor space of the evaporator; a pressure transmitting connection between the trap and a point within the evaporator below the liquid level therein; a float in said float chamber connected to close said valve upon a rise of liquid level in said chamber; and means for feeding liquid refrigerant at a restricted rate to said chamber.
10. The combination with an evaporator, of means for maintaining a desired liquid level therein comprising a valve controlling the supply of liquid refrigerant to the evaporator; a float chamber and a liquid sealed trap arranged to define a manometer column; a pressure equalizing connection from the float chamber to the vapor space of the evaporator; a vapor filled pressure transmitting

- connection between the trap and a point within the evaporator below the liquid level therein; means for varying the vertical height of said vapor filled connection; a float in said 5 float chamber connected to close said valve upon a rise of liquid level in said chamber; and means for feeding liquid refrigerant at a restricted rate to said chamber.
11. The combination with an evaporator, 10 of means for maintaining a desired liquid level therein comprising a valve controlling the supply of liquid refrigerant to the evaporator; a float chamber and a liquid sealed trap arranged to define a manometer column; 15 a pressure equalizing connection from the float chamber to the vapor space of the evaporator; a vapor filled pressure transmitting connection between the trap and a point within the evaporator below the liquid level therein; 20 means for adjusting vertically the lower end of said vapor filled connection; a float in said float chamber connected to close said valve upon a rise of liquid level in said chamber; and means for feeding liquid refrigerant at a restricted rate to said chamber.
12. The combination with an evaporator, 25 of means for maintaining a desired liquid level therein, comprising a valve controlling the supply of liquid refrigerant to the evaporator; a manometer column; a pressure equalizing connection from the top of the manometer column to the vapor space of the evaporator; a vapor filled pressure transmitting connection between the lower end of the manometer column and a point in the evaporator below the desired liquid level therein; a trap interposed between the pressure transmitting connection and the lower end of the manometer column; means for adjusting the 35 trap to vary the height of the lower end of the manometer column; and means responsive to the height of the upper end of the manometer column for opening and closing said valve as said upper end falls and rises.
- 40 13. The combination with an evaporator, of means for maintaining a desired liquid level therein, comprising a valve controlling the supply of liquid refrigerant to the evaporator; a manometer column; a pressure equalizing connection from the top of the manometer column to the vapor space of the evaporator; a partially vapor-filled pressure transmitting connection between the lower end of the manometer column and a point in 45 the evaporator below the desired liquid level therein; a trap interposed between the pressure transmitting connection and the lower end of the manometer column; an adjustable vent leading from the lower portion of the 50 pressure transmitting connection to the vapor space in the evaporator and serving when adjusted to determine at will the lower end of the vapor filled portion thereof; and means responsive to the height of the upper end of 55 the manometer column for opening and clos-
- ing said valve as said upper end rises and falls.
14. The combination with an evaporator, 60 of means for maintaining a desired liquid level therein, comprising a fixed manometer containing a column of liquid refrigerant; a valve controlling the supply of liquid refrigerant to the evaporator; operating means for said valve responsive to the height of the liquid column in said manometer; a pressure transmitting connection between said manometer and a point within the evaporator below the liquid level therein; means for developing in said connection a refrigerant vapor pressure at least equal to the head of the liquid refrigerant at said point; and means associated with said pressure transmitting connection for varying the relation between the liquid column in the manometer and the height of liquid in the evaporator. 65
15. The combination with an evaporator, 70 of means for maintaining a desired liquid level therein, comprising a fixed manometer containing a column of liquid refrigerant; a valve controlling the supply of liquid refrigerant to the evaporator; operating means for said valve responsive to the height of the liquid column in said manometer; a pressure transmitting connection between the upper end of the manometer and the vapor space above 75 the liquid in the evaporator; a pressure transmitting connection between said manometer and a point within the evaporator below the liquid level therein; means for developing in said connection a refrigerant vapor pressure at least equal to the head of the liquid refrigerant at said point; and means associated with said pressure transmitting connection for varying the relation between the liquid column in the manometer and the height of 80 liquid in the evaporator. 85
16. The combination with an evaporator, 90 of means for maintaining a desired liquid level therein, comprising a fixed manometer containing a column of liquid refrigerant; a valve controlling the supply of liquid refrigerant to the evaporator; operating means for said valve responsive to the height of the liquid column in said manometer; a pressure transmitting connection between the upper end of the manometer and the vapor space above 95 the liquid in the evaporator; a pressure transmitting connection between said manometer and a point within the evaporator below the liquid level therein; means for developing in said connection a refrigerant vapor pressure at least equal to the head of the liquid refrigerant at said point; and means associated with said pressure transmitting connection for varying the relation between the liquid column in the manometer and the height of 100 liquid in the evaporator. 105
- In testimony whereof I have signed my name to this specification.
